(57) **CLAIM**

The ornamental design for a display screen with a graphical user interface, as shown and described.

DESCRIPTION

The file of this patent contains at least one drawing executed in color. Copies of this patent with color drawings will be provided by the Office upon request and payment of the necessary fee.

FIG. 1 is an elevational view of a first embodiment of a display screen with a graphical user interface showing our new design; and,

FIG. 2 is an elevational view of a second embodiment of a display screen with a graphical user interface showing our new design.

The outer broken line showing of a display screen forms no part of the claimed design. The other broken lines showing text and portions of the graphical user interface form no part of the claimed design.

**1 Claim, 2 Drawing Sheets
(2 of 2 Drawing Sheet(s) Filed in Color)**

FIG. 1

FIG. 2
